F. L. STERCHELE.
SAFETY WATCH POCKET.
APPLICATION FILED JUNE 13, 1921.

1,413,806.

Patented Apr. 25, 1922.

By my Attorney
Wm. H. Reid.

Inventor
F. L. Sterchele.

UNITED STATES PATENT OFFICE.

FELIX L. STERCHELE, OF BROOKLYN, NEW YORK.

SAFETY WATCH POCKET.

1,413,806.

Specification of Letters Patent. Patented Apr. 25, 1922.

Application filed June 13, 1921. Serial No. 477,236.

To all whom it may concern:

Be it known that I, FELIX L. STERCHELE, a subject of the King of Italy, and a resident of Brooklyn, in the county of Kings and State of New York, have invented certain new and useful Improvements in Safety Watch Pockets, of which the following is a specification.

This invention has reference to means for retaining a watch in the pocket of the person wearing it, so that it cannot fall out, or be forcibly removed, and will be held in the pocket by secure means, which means by the simple pressing on the lower portion of the pocket by the wearer, will be released from the holding means and can be removed; and which holding means when the watch is returned to the pocket will automatically engage the watch to lock it in the pocket against removal.

A further object of the invention is to provide a pocket of this character, that will serve to enclose and protect the watch from foreign substance, and also from being scratched or injured.

In the accompanying drawing showing one embodiment of my invention, Figure 1 illustrates the device in use in a vest pocket.

Fig. 2 shows the device in perspective in the closed position.

Fig. 3 shows the device in the opened position.

Fig. 4 is a top view of the frame members.

Fig. 5 is a side elevation.

Fig. 6 shows separated the hinged portion of the frame members.

Fig. 7 shows the latter connected.

Fig. 8 shows the coil spring for the hinge.

As shown, the device comprises two complementary members, that are hinged together and normally pressed by a spring to bring their edges together to enclose a watch, and provided with an opening in which the stem of the watch can project. These members have portions extending beyond the hinge that can be pressed together, to cause the members to open to receive the watch, and to release it. Such members also have on one or both of them, a projection to extend over the edge of the watch and prevent its removal by being pulled outwardly.

In the arrangement set forth herein, I provide a pair of frames 1 and 2 that are substantially identical, and may be formed of a piece of wire or rod. These are arranged substantially annular, and are shown

hinged together by a bar 3 at one portion; while at the opposite portion they have loops 4 and 5, extending oppositely to receive the watch stem, as shown. The one member 1 is provided with tubular hinged portions 6, 6, having ears 7, 7, that are apertured to engage the hinged rod 3. A loop portion 8 is provided at this end of the member 1, which may be a separate wire bent at each end to enter the hinged portions, while the ends of the ring also enter these hinged tubes from the opposite end, see Fig. 1, and such ends are secured therein by soldering or other means. The other wire frame 2 has a similar loop 9 and similar hinged portions 10, 10, which also receive the hinged rod 3, see Fig. 7.

A coil spring 12 is mounted on the hinged rod 3 with its extremities secured to the loops, 1 and 2, respectively, whereby the loops or frames are normally pressed together as in Fig. 2. In this position the loops 8 and 9 will extend apart, and upon being pressed toward each other will swing the frames on the hinged rod and cause them to separate at the upper end, containing bends 4 and 5; but as soon as released the frames will be again swung together.

These frames are each provided with a cover preferably of a flexible nature such as fabric or a piece of chamois that can be looped over the wire frame and suitably secured, as by stitches. This will form a comparatively closed casing, that can be opened by pressing the loops 8 and 9 together to insert the watch, and will be pressed together to enclose the watch when released, with the stem projecting at the opening between the frames. I further provide retaining means to hold the watch in the casing. If the watch were merely inserted between these members and then pulled upwardly the frames would tend to separate and release the watch. To prevent this I provide a projection on one or both of the frames that will pass over the edge of the watch near the stem and thus prevent the frame to be opened by pulling on the watch. As shown the frame 1 is provided with a loop 13 extending across and bent slightly downward, so it will project over the edge of the watch. The other frame 2 is provided with a similar loop 14, preferably on the opposite side of the stem opening, that will also extend across the watch. When the watch is inserted and the pocket closed, it will be im-

possible to withdraw the watch by pressure in an opposite direction from the hinged portion, because each hook will hold the watch in the pocket and prevent opening of 5 the pocket members by the watch. But pressure on the loop portions 8 and 9 will cause the inmembers to open, and the hook portions 13 and 14 will simply move laterally away from the watch and permit its withdrawal.

This device can be placed in a pocket, being indicated in Fig. 1 in a vest pocket, and the loop portions will rest against the bottom of the pocket. It will be understood 15 that by placing the fingers under the edge of the face and engaging opposite sides of the pocket, the loops can be pressed together which will open the pocket to receive the watch, and will also open the pocket to release the watch when inserted. Also mere 20 pressure on the outer loop against the outside of the pocket will serve to cause it to open. It will be further understood that the device can be sewed in the pocket by 25 one or both of these loop portions 8 and 9, or at any other portion desired.

A device of this character will effectually stop any unauthorized removal of the watch and it cannot be stolen from the pocket, nor 30 can it fall out. The pocket will also serve to envelope the watch and prevent its being tarnished or disfigured.

It is to be understood that various changes can be made by those skilled in this art, 35 within the purview of the claims, without departing from the spirit and scope of my invention.

What I claim is:

1. A safety watch pocket, comprising a 40 pair of covered frames hinged together at one side with an opening formed between

them at the opposite side when in the closed position, whereby the frames can enclose a watch with the stem projecting at the opening, a retaining piece on one or both of the 45 frames adjacent the opening extending downwardly across the central plane of the watch position arranged to prevent withdrawal of the watch in the closed position of the frames, and a spring on the frames 50 at the hinged portion normally holding the frames in the closed position.

2. A safety watch pocket, comprising a pair of wire frames substantially ring shaped that are hinged together at one side, 55 a flexible cover on each frame, each frame having at the opening portion a bend whereby the frames can enclose a watch with the stem projecting at the opening, each frame having a hook portion extending toward the 60 other frame beyond the central plane of the watch position to prevent withdrawal of the watch, and a spring connecting these frames to retain them in closed position.

3. A safety watch pocket, comprising a 65 pair of wire frames substantially ring shaped that are hinged together at one side, a flexible cover on each frame, each frame having at the opening portion a bend whereby the frames can enclose a watch with the 70 stem projecting at the opening, each frame having a hook portion extending toward the other frame beyond the central plane of the watch position to prevent withdrawal of the watch, and a spring connecting these frames 75 to retain them in closed position, each frame having a loop extension beyond the hinge arranged to be pressed together to cause the frames to open.

Signed at New York city, N. Y., on June 80
1921.

FELIX L. STERCHELE.
